UNITED STATES PATENT OFFICE.

ELMER A. SCOTT, JR., OF ATTLEBORO, MASSACHUSETTS.

PIN JOINT FOR BROOCHES AND LIKE PINS.

Application filed July 15, 1927. Serial No. 206,082.

My invention relates to a novel type of pin tongue pivoting and mounting means or joints preferably integrally formed from a thin metal plate adapted for use on brooches and like pins and the improved method of forming said joints.

In accordance with my invention a free tongue is integrally cut in said plate and so shaped by ordinary mechanical operations, preferably conducted on automatic machinery, as to form a suitable type of pivoting means or joint of the same stock as the plate, preferably from a tongue cut from the plate and thus integrally secured thereto. My invention is peculiarly applicable to plates made of this sheet metal, such as copper, brass, etc., where it becomes necessary to attach the free end of said tongue to said plate to form a firm mounting for the joint for said pin tongue. My invention specifically relates to the improved means and method I employ to firmly secure the free end of said tongue to the back plate when thin metal plates are employed to provide a firm pin tongue pivoting joint securely attached to said plate against movement in either direction, without materially increasing the number or the difficulty of the manufacturing steps.

These and such other objects of my invention as may hereinafter appear will be best understood from a description of the accompanying drawings which illustrate a completed embodiment thereof and diagrammatically illustrate the steps to be performed in the manufacture thereof.

In the drawings, Fig. 1 is a front elevation of a skeleton plate for pins, brooches and the like with my pin tongue pivoting means integrally formed therefrom and secured thereto.

Fig. 2 is a rear elevation of a plate blank with the first step in the process of manufacture of my completed article, namely, the cutting of the pin tongue hole and formation of the catch performed thereon.

Fig. 3 is a sectional view taken along the line 3—3 of Fig. 2.

Fig. 4 is a rear elevation of said plate with the next step in the manufacture of my improved pin tongue pivoting joint performed thereon, namely, the cutting out of the tongue with the locking lugs integrally projecting from each side thereof from the metal of the plate.

Fig. 5 is a sectional view taken along the line 5—5 of Fig. 4.

Fig. 6 is a rear elevation of said plate after the next step in the manufacture of my invention has been performed thereon, namely, with the pin tongue pivot pin receiving loop formed on the rear thereof and the free end of the tongue drawn towards the integral end in the channel cut out in said plate.

Fig. 7 is a sectional view taken along the line 7—7 of Fig. 6.

Fig. 8 is a rear elevation of the plate shown in the preceding views with the next step in the manufacture of my invention performed thereon, namely, with the pivot tongue blade inserted through the hole in the loop and the loop further crimped around the pivot pin thereof to firmly secure it thereto and yet permit pivotal movement thereof, further drawing over the laterally projecting lugs in the channel in opposite sides of said plate.

Fig. 9 is a sectional view taken along the line 9—9 of Fig. 8.

Fig. 10 is a rear elevation of the completed article after the last step in the process of its manufacture has been performed thereon, namely, that of pressing the laterally projecting lugs into the soft metal of the plate on opposite sides thereof to firmly secure said pin tongue pivoting means thereto against movement in opposite directions.

Fig. 11 is a sectional view taken along the line 11—11 of Fig. 10.

In the drawings, wherein like characters of reference generally indicate like parts throughout, 15 is a suitable plate preferably formed of thin metal, preferably a copper sheet, from which my invention is to be integrally formed in a manner to be explained. My invention can probably be best explained from its method of manufacture.

The first step in the manufacture of my invention may comprise cutting the pin tongue blade pivoting hole 16 near one end thereof and cutting and striking up from the plate the pin tongue catch 18 preferably near the opposite end thereof, which steps may be either done by hand or by suitable automatic machinery, as all the steps later to be described.

Figs. 4 and 5 illustrate the next step in the method of performing my invention, which comprises cutting through said plate prefer-

ably in the direction of the catch 18 to form the free tongue 20, having one end 22 thereof integrally secured to said plate 15 and inner and outer sets of lugs projecting laterally therefrom on each side thereof preferably spaced from each other the length of the metal in a loop 25 to be formed, the outer lugs 26 being preferably smaller than the inner lugs 24 so that they may be readily pushed through the inner lug holes 36 in the manner later described.

The next steps in the process are illustrated in Figs. 6 and 7 and these comprise dapping the tongue 20 toward the integral end 22 thereof to form a loop 25 containing the hole 16 on the upper end thereof to receive the pin tongue blade pivot pin 28 of a T pin preferably integrally attached centrally to the pivot pin blade 30. The formation of the loop 25 coincidentally draws the tongue 20 over in the cut out portion 32 from which the tongue 20 was cut until the outer lugs 26 come adjacent the inner lug holes 36 with the inner lugs 24 overlapping one side of the plate 15, the rear as shown. The outer lugs 26 will come immediately adjacent the laterally extending holes 36 in the cut out portion 32 from which the larger inner lugs 24 were cut, for as stated, the inner lugs 24 were spaced from the outer lugs 26 a distance substantially the length of the metal in a loop later to be formed.

The next step in the process comprises inserting the pin tongue blade 30 of a T pin having the pin tongue pivoting pin 28 integrally attached to the base thereof through the loop 25 until the pivot pin 28 thereof is loosely contained within said loop 25 and coincidentally therewith the smaller outer lugs 26 are pushed through the inner lug holes 36 until they lie on the opposite side of said plate 15 from the inner lugs 24.

Figs. 8 and 9 illustrate the next step in the manufacture thereof, which comprises compressing in any suitable manner the loop 25 around the pivot pin 28 tight enough to closely bind said pivot pin and yet permit free pivotal movement thereof with the pin tongue blade 30 swinging within the hole 16. It is apparent that this further compression of the loop 25 further draws the tongue in said cut out portion 32 toward the integral end thereof until the outer lugs 26 overlap the opposite side of the plate 15, the front as shown in Figs. 8 and 9.

The last step of the process is illustrated in Figs. 10 and 11 and comprises compressing the inner sets of lugs 24 overlapping the rear of the plate 15 forwardly into the soft metal of said plate 15 from the rear thereof and the outer sets of lugs 26 overlapping the front side of said plate 15 rearwardly into the soft metal of the plate 15 to form surfaces on each side of said metal plate substantially flush therewith. As stated, in

place of forming the lugs 24 and 26 and pressing them into the plate as shown in Fig. 10, other suitable means, such as soldering, etc., may be employed to secure the free end 27 of said tongue 20 to the plate 15.

It is thus obvious that when completed I have provided a suitable thin metal plate 15 for brooches and like pins, having a suitable pin tongue pivoting means or joint integrally formed thereon comprising a tongue 20 cut out from said plate having a pivot pin loop 25 projecting rearwardly from near the integral end 22 thereof adapted to enclose a pin pivot pin 28 and having a hole 16 therein of a size to permit free pivotal movement of the pin blade 30 therein and the free end 27 of said tongue 20 beyond said loop 25 firmly secured to said plate in the tongue channel 32 in one direction by a set of lugs 24 projecting integrally therefrom overlappingly pressed into one side of said plate and in the opposite direction by the lugs 26 projecting integrally laterally therefrom overlappingly pressed into the opposite side of said plate, and I have further provided in combination with such a means, a pin tongue catch 18 spaced from said pivoting means and a pin tongue blade 30 of a T pin having the pivot pin 28 at the base thereof firmly secured within said loop 25 to permit pivotal movement thereof through said hole 16. As stated, means such as solder, other than the lugs 24 and 26 may be provided to firmly attach the free end 27 of said tongue 20 to said plate 15 where said plate 15 is constructed out of soft metal.

It is apparent that I have provided a strong pin tongue pivoting means or joint firmly secured against movement to said plate integrally cut out and formed from the metal of the plate either by hand or by well known types of automatic machinery.

It is understood that my invention is not limited to the specific embodiment shown or method described and that various deviations may be made therefrom without departing from the spirit and scope of the appended claims.

What I claim is:

1. The herein described method of forming a pin tongue pivoting joint in and firmly securing it to a thin metal plate for brooches and like pins which comprises cutting through said plate to form a free tongue having one end thereof integrally secured to said plate, inner and outer sets of lugs projecting integrally laterally therefrom on each side thereof spaced from each other substantially the length of the metal in the later to be formed loop, and a hole near the integral end thereof, dapping said tongue towards the integral end thereof to form a loop containing said hole on the upper end thereof, coincidentally drawing the tongue over in the cut out portion until the outer

115

135

6 lugs come adjacent the inner lug holes, the inner lugs overlapping one side of said plate, inserting a pin tongue having a pivot pin integrally attached to the base thereof through said loop hole until the pivot pin is loosely contained within said loop, pushing the outer lugs through the inner lug holes until they lie on the opposite side of said plate from said inner lugs, compressing 10 the loop around said pivot pin tight enough to closely bind said pin and yet permit free pivotal movement thereof with the pin blade swinging within said hole, coincidentally further drawing over said tongue in said cut 15 out portion until the outer lugs overlap the opposite side of said plate, and compressing said inner and outer sets of overlapping lugs into said plate on opposite sides thereof.

2. The herein described method of forming a pin tongue pivoting joint in and firmly securing it to a thin metal plate for brooches and like pins which comprises cutting through said plate to form a free tongue having one end thereof integrally secured 25 to said plate, sets of lugs projecting laterally therefrom on each side thereof, and a hole near the integral end thereof, inserting a pin tongue having a pivot pin attached to the base thereof through said hole from the rear thereof, compressing the portion of said tongue adjacent the integral end thereof around said pivot pin to form a rearwardly projecting loop tight enough to closely bind said pivot pin and yet permit free pivotal 30 movement thereof within, simultaneously drawing the free end of said tongue in said cut out portion towards said integral end with one set of lugs overlapping the front of said plate and the other set of lugs overlapping the rear of said plate, and compressing 35 said sets of overlapping lugs into said plate on opposite sides thereof.

3. The herein described method of forming a pin tongue pivoting joint in and firmly securing it to a thin metal plate for brooches and like pins which comprises cutting through said plate to form a free tongue having one end thereof integrally secured to said plate, and a hole near the 45 integral end thereof, inserting a pin tongue having a pivot pin attached to the base thereof through said hole from the rear thereof, compressing the portion of said tongue adjacent the integral end thereof around said pivot pin to form a rearwardly projecting loop tight enough to closely bind said pivot pin and yet permit free pivotal movement thereof within, simultaneously drawing the free end of said tongue in said 50 cut away portion towards said integral end, and firmly securing the free end of said tongue to said plate.

4. A pin tongue pivoting joint for thin sheet metal plates for brooches and like pins 55 comprising a T pin tongue blade having a

pivot pin, a thin sheet metal plate having a pin tongue blade catch integrally rearwardly struck up from a portion of said plate and a pin tongue pivoting joint integrally struck up from another portion of the plate thereof spaced substantially the pin blade length from said catch comprising a tongue projecting in the direction of the pin blade cut away from said base except at the integral outer end thereof and having sets of lugs projecting laterally therefrom, dapped rearwardly in the cut away portion of said base to form a loop compressed around the pivot pin to permit swinging movement thereof, having a hole to permit 70 swinging movement of the pin blade therein, the free end of said tongue drawn over in the cut away portion being firmly secured to said base by one set of said lugs overlapping the front of said base and the other set 75 of lugs overlapping the rear of said base, said lugs being compressed into said base.

5. In combination, a T pin tongue blade having a pivot pin at the base thereof, a thin metal plate having a pin tongue blade catch projecting rearwardly therefrom and a pin tongue pivoting joint integrally formed on another portion thereof spaced substantially the blade length from the catch comprising a tongue having an end integral with 80 said plate cut out from said plate in a line with said catch, with sets of lugs projecting laterally therefrom near the free end thereof, having a rearwardly projecting loop near the integral end thereof, having a hole in the upper end thereof compressed around the pivot pin to permit pivotal movement of said pin within and said blade within said hole and the end of said tongue beyond said loop firmly secured to said plate in one direction 85 by one set of said lugs overlapping the edge of said tongue channel pressed into said plate on one side thereof and in the opposite direction by another set of said lugs overlapping the edge of said tongue channel 90 pressed into said plate on the opposite side thereof.

6. In combination, a pin tongue blade having a pivot pin at the base thereof, a thin metal plate having a pin tongue blade catch 95 projecting rearwardly therefrom and a pin tongue pivoting joint integrally formed on another portion thereof spaced substantially the blade length from the catch comprising a tongue having an end integral with said plate cut out from said plate in a line with said catch, having a rearwardly projecting loop near the integral end thereof having a hole in the upper end thereof compressed around the pivot pin to permit pivotal movement of said pin within and said blade within said hole, and the end of said tongue beyond said loop firmly secured to said plate.

7. A thin metal plate for brooches and 100

like pins having a pin tongue pivoting joint integrally formed thereon comprising a tongue cut out from said plate having a pin pivot pin loop projecting rearwardly from near the integral end thereof adapted to enclose a pin pivot pin having a hole therein of a size to permit pivotal movement of the blade therein, and the free end of said tongue beyond said loop firmly secured to

said plate in said tongue channel in one 10 direction by lugs projecting integrally laterally therefrom overlappingly pressed into one side of said plate and in the opposite direction by lugs projecting integrally laterally therefrom overlappingly pressed into 15 the opposite side of said plate.

In testimony whereof I affix my signature.
ELMER A. SCOTT, JR.
